Patented May 16, 1922.

UNITED STATES PATENT OFFICE.

FRED E. SHOURDS, OF HETLAND, SOUTH DAKOTA.

HAMMER.

1,415,956.

Specification of Letters Patent. Patented May 16, 1922.

Application filed May 22, 1920. Serial No. 383,428.

To all whom it may concern:

Be it known that I, FRED E. SHOURDS, citizen of the United States, residing at Hetland, in the county of Kingsbury and State 5 of South Dakota, have invented certain new and useful Improvements in Hammers, of which the following is a specification, reference being had therein to the accompanying drawings.

10 This invention relates to improvements in hammers, and has for its object the construction of a hammer which not only embodies the elements of an ordinary hammer, but also novel features, whereby a leverage 15 or fulcrum can be secured, in addition to other features, making the hammer admirably suited for wrecking or tearing down of building purposes.

With this and other objects in view, my 20 invention comprises certain novel combinations, constructions and arrangements of parts as will be hereinafter described, illustrated in the accompanying drawings, and more particularly pointed out in the appended claim.

In the drawings:

Figure 1 is a perspective view of a hammer constructed in accordance with the present invention, while

30 Figure 2 is a front view of the same.

Figure 3 is a longitudinal sectional view of the hammer.

Figure 4 is a sectional view taken on line 4—4, Fig. 3, and looking in the direction of 35 the arrows.

Referring to the drawings by numerals 1 designates the body of the hammer, into which extends the handle 2.

The body 1 is provided, at its "rear" or 40 outer end, with a head 3. The body has extending from its front or forward end, an elongated chisel-forming portion 4, and on this chisel-forming portion 4 and extending parallel therewith is a reinforcing rib 5.

45 The chisel-forming portion 4 and rib 5 merge at their outer ends into a comparatively broad portion 6, which portion 6 and rib 5 has a smooth flat face 7, formed in the arc of a circle, the rib 5 being outwardly pro-

50 truding so that the rib 5 and body 1 forms an admirable fulcrum for facilitating the removal of nails from a board, or the removal of a board from a support to which it is tacked, or secured, without undue strain being placed upon the handle 2.

The comparatively broad portion 6 ter-

minates in claws 8, that have comparatively blunt ends 9 (Fig. 3) so as to strengthen these claw ends 8 or not weaken the chisel structure of the hammer. The claws 8 are 60 separated by a V-shaped notch 10, which V-shaped notch is contiguous to a concave socket 11. This notch 10 receives the shank of a nail or tack, while the socket 11 receives the head. 65

By reason of the comparatively long structure of the chisel and claw ends of the hammer, the same can be pushed or forced under a board, and then the board raised or removed from its support, through the action 70 of the rounded or outwardly-extending rib structure 5, which rib merges, at its inner or rear portion, into the body 1 of the hammer.

By referring to Figures 1, 2, and 4, it will be seen that the reinforcing rib is comparatively narrow in cross-section. Therefore, when the hammer is in use and is being rocked upon the rib 5, the pressure brought to bear upon the narrow contact surface of the rib will cause the rib to have an increased binding action upon the support 75 upon which the hammer is resting, or if the support should happen to be rather soft, as when the hammer is resting upon wood, the rib will slightly dig into the support. This 80 binding or digging action will positively hold the head against side slipping or displacement, so that the hammer is held in position for proper and positive action at all 85 times when the same is in use. Thus it will 90 be seen that the rib not only reinforces the chisel-forming portion and also provides a surface upon which the hammer rocks, but also acts as a retainer for holding the hammer properly when in operation. 95

While I have described the preferred embodiment of my invention, and have illustrated the same in the accompanying drawings, certain minor changes or alterations may appear to one skilled in the art to which 100 this invention relates, during the extensive manufacture of the same and I, therefore, reserve the right to make such alterations or changes as shall fairly fall within the scope of the appended claim. 105

What I claim is:

As a new article of manufacture, a hammer consisting of a body, having a forward end and a head, an elongated chisel-forming portion extending from said body, of a 110 raised longitudinally extending reinforcing rib formed centrally upon said chisel-form-

ing portion, one end of said rib merging in the forward end of said body, said chisel-forming portion and the opposite end portion of said rib merging into a broad notched 5 portion, said rib and chisel-forming portion being curved throughout their entire lengths, said rib being comparatively nar-

row in cross section, whereby the rib will hold the hammer against side slipping when the device is in use and the hammer is being 10 rocked upon said rib.

In testimony whereof I hereunto affix my signature.

FRED E. SHOURDS.
